**PNEUMATIC ROCK DRILL MUFFLER WITH
WATER MINGLING PIPE**
Raymond L. Lindberg, Rte. 1, Box 311, Bessemer, Mich.
Filed Oct. 8, 1964, Ser. No. 402,593
8 Claims. (Cl. 181—52)

The present invention generally relates to pneumatic rock drills, and is more particularly concerned with the provision of a non-freezing muffler for such drills.

One of the primary objects of the instant invention is to provide an effective compact muffler which can be mounted directly on a conventional pneumatic rock drill so as to effectively accommodate the exhaust coming therefrom.

Another significant object of the instant invention is to provide a muffler wherein a constant spray of water is utilized so as to prevent a freeze-up of the inlet and outlet ports thereof.

Furthermore, it is an object of the instant invention to provide a muffler which, though relatively simple in construction, is of a sturdy nature capable of withstanding the shocks to which it will be subjected during normal operation of the drill.

Basically, in achieving the above objects, it is contemplated that the muffler of the instant invention include an elongated cylindrical closed chamber having an exhaust inlet port communicating laterally therewith adjacent one end, and an exhaust outlet port communicating coaxially with the other end. In addition, the freeze-up preventing water is to be introduced to both the inlet port and the outlet port through an elongated water pipe extending longitudinally through the chamber and having a laterally directed discharge nozzle thereon extending to the inlet port while the extreme end of the water pipe extends to the outlet port. Finally, it is contemplated that a plurality of baffles be provided transversely across the chamber with these baffles constructed and orientated so as to cause a constant rotational movement of the fluid as it passes through the chamber so as to also prevent the freeze-up within the chamber itself.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a partial plan view illustrating the muffler of the instant invention mounted in position upon a pneumatic drill;

FIGURE 2 is an enlarged partial cross-sectional view taken substantially on a plane passing along line 2—2 in FIGURE 1;

FIGURE 3 is a cross-sectional view taken substantially on a plane passing along line 3—3 in FIGURE 2; and

FIGURE 4 is a cross-sectional view taken substantially on a plane passing along line 4—4 in FIGURE 2.

Referring now more specifically to the drawings, reference numeral 10 is used to generally designate the muffler comprising the instant invention. The muffler 10 consists basically of an elongated hollow tubular shell 12 defining an elongated cylindrical chamber 14 having closed forward and rear ends 16 and 18. Slightly forward of the closed rear end 18 of the chamber 14 is an exhaust inlet port 20, provided with a projecting cylindrical pipe section for communication with the exhaust port of a conventional pneumatic rock drill 22. The other or forward end 16 of the tubular member 12 is provided with a greatly enlarged exhaust outlet port 24 provided with a forwardly projecting cylindrical pipe section 26 to which a discharge hose 28 is to be clamped, this hose 28 dis-

posing of the discharge from the muffler 10 remote from the drill 22.

Extending coaxially through the chamber 14 is an elongated water pipe 30 which is communicated to a suitable valve controlled source of pressurized water. The forward end 32 of the water pipe 30 is located adjacent to or within the exhaust outlet port 24 so as to provide a constant spray of water both on the outlet port 24 and the interior of the pipe section 26 so as to prevent a freeze-up resulting from the normally chilled condition of the exhaust. In addition, through a T-fitting 34, a laterally directed spray nozzle 36 is aligned with the exhaust intake port 20 so as to spray water thereon during the operation of the drill. The spray from the nozzle 36 is of course not sufficient so as to axially discharge through the intake port 20 against the inward flow of the exhaust, and is carried along through the chamber 14 and out the outlet port 24 by the exhaust flow. The spray from the open end 32 of the pipe 30 mingles with the exhaust and prevents the freeze-up which might be normally expected.

In order to prevent freeze-up within the muffler chamber 14, a constant agitation or rotation of the water flowing therethrough is effected. This is accomplished by the provision of radially extending angularly orientated fins 38 on a plurality of longitudinally spaced baffles 40. The baffles 40 include central apertured hubs 42 which receive and support the water pipe 30 while the outer ends of the fins 38 are welded directly to the interior of the chamber 14 at peripherally spaced points thereabout. As illustrated in the drawings, if so desired, the fins 38 on the baffles 40 can be angled in opposite directions so as to initially cause a rotation of the water flowing through the chamber in one direction and subsequently reversing the rotational movement, this constant movement preventing the presence of dead water on the bottom of the chamber 14 such as might tend to freeze. As will be appreciated, various other types of baffles may be used, although it should be appreciated that these baffles should incorporate some configuration which will tend to maintain a constant agitation of the water flowing through the chamber 14. FIGURE 4 illustrates a baffle 44 having radially projecting flat fins which is to complete the particular baffle arrangement illustrated in the drawings.

The muffler 10 is mounted on a conventional rock drill 22 through one or two adjustable clamps 46 engaged over projecting brackets 48 welded to the tubular chamber forming member 12. In operation, the exhaust from the drill 22 is introduced into the muffler through the inlet port 20 where it is immediately commingled with water sprayed from the nozzle 36 with the combined water and exhaust moving through the cylindrical chamber 14 and maintained in constant rotational movement until discharge through the exhaust outlet port 24 where a second constant discharge of water takes place so as to also prevent freeze-up at this point. As noted supra, the outlet port is substantially larger than the inlet port so as to avoid any back pressure and insure a complete and efficient discharge of both the water and exhausted air. In this manner, a highly efficient muffling of the cold exhaust from a pneumatic rock drill is achieved without the undesirable freeze-up which might normally be expected in attempting to provide for such a muffling. Incidentally, while three baffles have been specifically illustrated, it should be appreciated that any reasonable number of baffles can be used. Further, if necessary to prevent freeze-up, laterally directed holes can be provided in water pipe 30 so as to spray water directly on the baffles.

The foregoing is considered as illustrative only of the principles of the invention. Further, since numerous

modifications and changes will readily occur to those skilled in the art, it is not desired to limit the invention to the exact construction and operation shown and described, and accordingly all suitable modifications and equivalents may be resorted to, falling within the scope of the invention, as claimed.

What is claimed as new is as follows:

1. A muffler for a pneumatic rock drill comprising an elongated closed cylindrical chamber, an exhaust inlet port in the chamber adjacent one end thereof, an exhaust outlet port in the chamber adjacent the other end thereof, an elongated water pipe extending longitudinally through said chamber, a first discharge opening in said pipe directed toward the inlet port, a second discharge opening in said pipe directed toward the outlet port, and a plurality of spaced baffles oriented in said chamber so as to produce an agitation of fluid passing through the chamber.

2. The device of claim 1 wherein said outlet port is larger than the inlet port and acts so as to discharge both the exhaust from the pneumatic drill and the water mixed therewith.

3. The device of claim 1 wherein said first discharge opening is in substantial coaxial alignment with said inlet port, and said second discharge opening is in substantial coaxial alignment with said outlet port.

4. The device of claim 1 wherein at least two baffles are provided, each of said baffles having radially extending angularly orientated fins, the fins on each baffle being angled oppositely from the fins on the other baffle so as to effect a reversal of the agitated flow through said chamber.

5. A muffler for a pneumatic rock drill comprising a closed chamber, an exhaust inlet port in the chamber, an exhaust outlet port in the chamber in spaced relation to said inlet port, a water pipe located within said chamber, a first discharge opening in said pipe directed toward the inlet port, a second discharge opening in said pipe directed toward the outlet port and baffle means located within

said chamber so as to produce an agitation of the fluid passing through the chamber.

6. The device of claim 5 wherein said chamber is elongated, said inlet port and said outlet port being located adjacent opposite ends of said elongated chamber, said baffle means comprising a plurality of spaced baffles oriented within said chamber between said inlet port and said outlet port.

7. The device of claim 5 wherein said first discharge opening is in substantial coaxial alignment with said inlet port, and said second discharge opening is in substantial coaxial alignment with said outlet port.

8. A muffler for a pneumatic rock drill comprising an elongated closed chamber, an exhaust inlet port in the chamber adjacent one end thereof, an exhaust outlet port in the chamber in spaced relation to said inlet port, an elongated water pipe located within said chamber, a first discharge opening in said pipe directed toward the inlet port in substantial coaxial alignment therewith, and a second discharge opening in said pipe directed toward the outlet port in substantial coaxial alignment therewith.
